UNITED STATES PATENT OFFICE.

FRANK KUHN AND JAY A. HAND, OF DETROIT, MICHIGAN, ASSIGNORS TO AMERICAN ELECTRICAL HEATER COMPANY, OF DETROIT, MICHIGAN, A CORPORATION OF MICHIGAN.

ELECTRICAL HEATING UNIT.

1,307,587.

Specification of Letters Patent. Patented June 24, 1919.

Application filed January 18, 1917. Serial No. 143,158.

To all whom it may concern:

Be it known that we, FRANK KUHN and JAY A. HAND, both citizens of the United States of America, residing at Detroit, in 5 the county of Wayne and State of Michigan, have invented certain new and useful Improvements in Electrical Heating Units, of which the following is a specification, reference being had therein to the accompanying 10 drawings.

The invention relates to electrical heating units of the type in which the resistor is supported in a refractory insulator base. One form of unit of this type is that in 15 which the insulator base is provided with a spiral groove in the face thereof in which the resistor is laid, the depth of the groove being sufficient to prevent contact between the resistor and the utensil to be heated supported on the base. There is, however, danger that the contents of the utensil may be spilled upon the base, thereby short-circuiting the resistor. With our improved construction this danger is avoided by filling 20 the spiral groove above the resistor with a refractory insulating material and one which is a good conductor of heat.

Another defect of the constructions heretofore used is the danger of cracking of the 30 insulator base, due to the greater heat imparted to the central portion thereof than that which is communicated to the peripheral portion. This we have avoided by a series of slits in the periphery, which permit unequal expansion and contraction without danger of fracture.

In the drawings:

Figure 1 is a perspective view of the unit; Fig. 2 is a cross-section thereof;

40 Fig. 3 is a bottom plan view.

A is a disk-shaped insulator base, formed of a suitable refractory material and provided with a spiral groove B in its upper face for receiving the resistor C. At the 45 periphery of the base is a depending flange D, and radially extending ribs E on the bottom of the base serve to brace and strengthen the same. F is a lateral extension at one side of the base, on which the terminal contacts G are mounted. In assembling 50

the unit the resistor C is first laid in the spiral groove B and the terminal ends are connected to the contacts G. The groove B is then filled with a plastic heat-conducting material H, flush with the upper face of the 55 base. The filling material is preferably a better heat conductor than the material from which the base is formed, and consequently the heat of the resistor is to a large extent conducted upward through this material. 60

At the periphery of the base there are a number of radial slots I, which pass completely through the flange D at a point intermediate the connection of the ribs E thereto. These slots will permit the slight 65 separation of the segments on opposite sides thereof, so that when the center of the base is heated to a greater degree than the periphery, there is no danger of fracture.

What we claim as our invention is:

1. In an electrical heating unit, the combination with a refractory base having a grooved upper face, of a resistor located in said groove, and a filling for said groove of a refractory material having a greater 75 heat conductivity than the body of the base.

2. In an electrical heating unit, a base formed of refractory material and provided with a peripheral flange and radial ribs, said peripheral flange being slotted to divide 80 the same into a number of separate segments, and a resistor embedded in said base.

3. In an electrical heating unit, the combination with a base of refractory material, having a spiral groove in the upper face 85 thereof and provided with a peripheral flange and radial strengthening ribs in the bottom portion, said peripheral flange being slotted at intervals to divide the same into a plurality of separate segments, a resistor 90 arranged in said spiral groove, and a filling in said groove of refractory material having a greater heat conductivity than the body of the base, said filling being flush with the upper face of the base. 90

4. An electrical heating unit, comprising a refractory base provided with a grooved surface having a plurality of revolutions surrounding each other, and a resistor mounted in said groove, said base having inwardly 100

extending slits in its periphery to divide the same into a number of separate segments.

5. An electrical heating unit, comprising a refractory base and a resistor embedded therein, said base having inwardly extending slits in its periphery to divide the same into a number of separate parts.

In testimony whereof we affix our signatures in presence of two witnesses.

FRANK KUHN.
JAY A. HAND.
